UNITED STATES PATENT OFFICE.

HUBERT L. CLARY, OF WELDON, NORTH CAROLINA.

ADJUSTABLE AND REVERSIBLE LADDER FOOT.

Application filed January 18, 1922. Serial No. 530,192.

This invention relates to ladders, and the primary object of the present invention is the provision of means, for connection with ladders of the ordinary character, for permitting effective use of ladders on different kinds of polished surfaces, that is, surfaces, such as floors, steps and the like, and surfaces of a relatively soft nature, such as the ground, such means acting to prevent the slipping of the ladder when in use on different kinds of surfaces, and the marring of floors and the like.

Another object of the invention is the provision of a novel foot for ladders having independent surface engaging members formed on the opposite ends thereof, said members having different characteristics for engaging surfaces of different kinds, whereby the ladder can be effectively used for all purposes and under all conditions.

Other objects of the invention are first, the provision of a ladder foot of novel form embodying a member on one end thereof for engaging a polished surface and a member on the opposite end thereof for engaging a soft surface, or a surface in which the marring thereof is inconsequential; second, to form a novel means for connecting the foot to the ladder whereby the same can be readily reversed to permit the different members formed thereon to be brought into an active position and to permit the foot to be readily and quickly secured to or removed from the ladder with which it is associated; and third, to provide a novel means associated with the foot for bracing or strengthening the ladder stringers or legs, with which the foot is connected.

A further object of the invention is the provision of a reversible foot for each stringer or leg of a ladder, having novel means for permitting the feet to be adjusted in relation to each other, whereby the ladder can be conveniently used on uneven surfaces, such as steps, roofs having inclined surfaces, and the like.

A still further object of the invention is to provide reversible and adjustable feet for ladders of the above character, which will be durable and efficient in use, simple and easy to manufacture, and which can be placed upon the market and incorporated with ordinary ladders at a minimum cost.

With these and other objects in view, the invention consists in the novel construc-

tion, arrangement and formation of parts, as will be hereinafter more specifically described, claimed and illustrated in the accompanying drawings, forming a part of this specification, in which drawings:

Figure 1 is a perspective view of a step ladder equipped with the improved reversible and adjustable feet, showing the use of the ladder on a stair case, the padded or polished surface engaging ends being disposed lowermost, the feet on the legs of the step portion of the ladder being adapted to engage a step in a plane below the step which is engaged by the feet carried by legs of the prop section of the ladder.

Figure 2 is a perspective view of a step ladder equipped with the improved reversible and adjustable feet, showing the ladder in use on a pitched roof, the feet having their pointed ends disposed lowermost, the feet carried by one leg of the prop section and one leg of the step section being disposed below the feet of the other portions of the ladder, whereby the top platform and the steps of the ladder can be held in a horizontal plane.

Figure 3 is an enlarged side elevation of one of the improved feet, showing the same in an adjusted position in relation to the leg or stringer of a ladder.

Figure 4 is an enlarged perspective view of one of the improved feet showing the padded end thereof for engaging a polished surface, the foot being shown attached to the leg or stringer of a ladder.

Figure 5 is a detail transverse section through one of the improved feet and the leg or stringer of the ladder, taken on the line 5—5 of Figure 3.

Figure 6 is an enlarged detail perspective view of one of the locking blocks, utilized for holding the feet in their adjusted positions.

Figure 7 is an enlarged detail sectional view through one end of one of the feet, illustrating the means of connecting the pad thereto for engaging a polished surface.

Referring to the drawings in detail, wherein similar reference characters designate corresponding parts throughout the several views, the letter A generally indicates a preferred form of the improved reversible and adjustable ladder foot, which includes a body 105 preferably formed of metal. This body 5 can be cast or formed in any other desired 110

way, and is adapted to be adjustably associated with the leg or stringer of a ladder as will be hereinafter more fully described. The opposite ends of the foot 5 are provided with surface engaging elements 6 and 7 of different characters, which permits the effective use of a ladder equipped with the foot for a variety of different purposes.

The surface engaging element 6 is adapted to be used on plane surfaces having a polished face, such as floors, steps or the like, in which the marring thereof would be detrimental thereto. This surface engaging element 6 includes a laterally projecting member of ear 8, which forms a relatively large bearing face. A pad 9 preferably formed of rubber is secured to the outer end of the lug or member 8, and this pad 9 is adapted to engage the surface on which the ladder is placed, and serves the dual function of preventing the marring of the surface, and preventing the slipping of the ladder. In order to enhance the gripping qualities of the rubber pad 9, the outer or active face thereof may be corrugated or roughened as at 10, and this corrugated or roughened surface will form an effective means for engaging a floor or other polished surface. The outer face of the lug or element 8 may be recessed as at 11 for the reception of the pad 9, and the pad may be held in the recessed portion by suitable fastening elements 12, which can be countersunk in the pad 9, as at 13.

The surface engaging element 7, which is disposed on the opposite end of the body 5 from the surface engaging element 6 is provided with a pointed terminal 14, for digging or biting into the surface on which the ladder may be placed. This surface engaging element 7 is specifically adapted to be used when the ladder is placed on the ground or some other surface where the marring thereof is inconsequential. The outer longitudinal face of the body 5 is provided with a longitudinally extending recessed portion 15, which may extend from the surface engaging element 6 to the surface engaging element 7. The body 5, at the longitudinal center of the recessed portion 15, is provided with a longitudinally extending slot 16, and this slot extends the entire length of the recessed portion 15. The inner face of the recessed portion 15 on opposite sides of the slot 16 is provided with a corrugated or toothed face 17, the purpose of which will hereinafter more fully appear.

A reinforcing metal plate 18 is adapted to be secured to the inner surface of each leg of a ladder, with which the improved feet 5 are associated, and the reinforcing plate can be held in position by means of a suitable wood screw or the like 19. The plate 18 on opposite sides of the screw 19 support inwardly extending retaining bolts 20, the heads of which may be countersunk in the

plate 18 as at 21. These bolts 20 are adapted to extend through the leg of the ladder with which the plate is associated, and are of such a length as to extend through the slot 16 formed in the body 5 and outwardly of the outer face of the body. The ends of the bolts 20 which protrude through and beyond the body 5, are threaded as at 22 for the reception of nuts 23, which may be provided with handles 24 to facilitate the turning thereof. Each one of the bolts 20 also receives a locking block 25, which is also preferably formed of metal. Each of the blocks 25 includes a plate 26, having a centrally disposed transversely extending wedge shaped extension 27, which is adapted to slidably fit within the slot 16, the side walls of which are inclined inwardly. Each block is of such a width as to fit or extend across the recessed portion 15, and the inner face of each block on opposite sides of the wedge shaped extension 27 is provided with teeth or corrugations 28 for engaging the corrugations or teeth 17 of the recessed portion 15 of the body 5. Each block is provided with a bore or opening 29, for the reception of the bolt 20, and it is obvious that by tightening the nuts 23, the blocks 25 can be forced into intimate locking contact with the body 5 and hold the same in an adjusted position on the leg of a ladder. While two bolts 20 and two locking blocks 25 have been shown, it is to be understood that more or less bolts and locking blocks can be utilized without departing from the spirit or scope of the invention.

In Figures 1 and 2 is illustrated the use of the improved feet A, with a step ladder, which is designated by the reference character D.

The step ladder D can be of the usual or any preferred character, and as shown includes the step portion 35 and the prop section 36. The legs or stringers 37 of the step portion 35 and the legs or standards 38 of the prop section 36 have each associated therewith one of the improved feet A and these feet A are connected to the legs 37 and 38 in the same manner as hereinbefore described.

In Figure 1, the step ladder 35 is shown as used on a stair case E and the legs or standards 38 of the prop section 36 engage a step 39 disposed in a plane above the step 40, on which the legs or stringers 37 of the step section 35 are disposed. The feet A carried by the legs 37 of the step section 35 are adjusted so that the lower ends thereof will extend in a plane below the lower ends of the feet A carried by the legs or stringers 38 of the prop section 36 and thus permit the steps or the rungs of the step section 35 to be disposed in a horizontal plane. The bodies 5 of all of the feet A have the surface engaging elements 6 disposed lower.

most so that the feet will not mar the surface of the steps on which the ladder is being used.

In Figure 2, the ladder 35 is shown used on an inclined or pitched roof F and in this use of the ladder, the surface engaging elements 7 are disposed lowermost. In order that the rungs or steps of the ladder D will be held in a horizontal plane on an inclined roof, the foot A carried by one leg 37 of the step portion 35, is adjusted so that the surface engaging element extends below the lower end of the surface engaging element 7, carried by the foot A secured to the other leg 37 of the step section 35. The foot A carried by the leg or standard 38 of the prop section 36, which is directly opposite to the mentioned leg of the step section 35 has the body 5 thereof adjusted, so that the lower end of the surface engaging member 7, will be disposed in the same plane as the lower end of the mentioned foot A carried by the leg of the step section 35. Adjustment of the bodies 5 of the mentioned feet A will permit the rungs or steps of the ladder to be effectively held in a horizontal plane and thereby facilitate the climbing of the ladder, it being understood of course, that the bodies 5 of the mentioned feet A are adjusted to conform to the pitch or inclination of the roof F.

When it is desired to change or reverse the position of the bodies 5 of the feet A, it is merely necessary to remove the nuts 23 and the adjusting blocks 25, from off of the bolts 20 and remove the bodies 5 from out of engagement with the legs of the ladder and the bolts 20, after which the bodies 5 may be reversed and then replaced in engagement with the legs of the ladder and the locking blocks 25 replaced on the bolts 20 and the nuts 23 rethreaded on the bolts so as to force the locking blocks in locking engagement with the corrugated or toothed faces 17 of the recess portions 15. It is apparent that when the locking blocks 25 are forced into contact with the corrugated or toothed faces 17 of the recessed portions 15, that the bodies 5 of the feet A will be held in adjusted position.

From the foregoing description, it can be seen that an improved foot for ladders has been provided which will effectively permit the use of ladders, on uneven surfaces, inclined surfaces, and other surfaces of different characters. While the improved foot is shown in the drawings and described as

applied to step ladders, it is to be understood that such is merely by way of example, since the improved foot may be readily applied to various types of ladders as will be obvious from the foregoing.

Changes in details may be made without departing from the spirit or scope of this invention; but,

I claim:

1. The combination with a ladder including a leg, of an adjustable and reversible foot associated with the leg including a body, surface engaging members having different characteristics formed on the opposite ends of the body, the body having one face thereof provided with a longitudinally extending recess and a slot disposed intermediate the side edges of the recess, the inner face of the recess being provided with teeth upon opposite sides of the slot, a reinforcing and bracing plate secured to one face of the leg adjacent to the lower end thereof, bolts carried by the plate and extending through the leg of the ladder and through the slot in the body, locking blocks slidably mounted on the bolts including a plate, an inwardly extending wedge shaped lug formed on the last mentioned plate and arranged to extend in the slot, and teeth disposed on the plate on opposite sides of the lug engaging the teeth formed on the inner wall of the recess, and adjustable nuts threaded on the bolts for engaging said locking blocks.

2. The combination with a ladder including a leg, of an adjustable and reversible foot for the ladder comprising a body, surface engaging members having different characteristics carried by the opposite ends of the body, the body having one face thereof provided with a longitudinally extending recessed portion, a longitudinal slot disposed intermediate the side walls of the recessed portion, inverted V shaped teeth formed on the bottom of the recessed portion on opposite sides of the slot, the ridges of said teeth being disposed flush with one face of the body, a bolt carried by the leg of the ladder and extending through said slot, an adjustable plate slidably mounted upon the bolt having teeth formed thereon for engagement with the teeth formed on the inner wall of the recess, and a nut threaded on the bolt for engagement with said plate.

HUBERT L. CLARY.
